Inventor
Robert S. MacLean
Williams Bradford
McCahill & Pearce Attest

UNITED STATES PATENT OFFICE.

ROBERT S. MACLEAN, OF CHICAGO, ILLINOIS.

BUILDING CONSTRUCTION.

Application filed July 31, 1922. Serial No. 578,564.

To all whom it may concern:

Be it known that I, ROBERT S. MACLEAN, a citizen of the United States, and resident of Chicago, in the county of Cook and State 5 of Illinois, have invented certain new and useful Improvements in Building Construction, of which the following is a full, clear, concise, and exact description, reference being had to the accompanying drawings, 10 forming a part of this specification.

My invention relates to improvements in building construction, and is particularly concerned with a novel type of covering for the exposed surfaces of a building. While 15 the covering forming a part of my invention is particularly designed for the roofs of buildings, it may be used equally well for covering the sides or other exposed surfaces of a building.

20 The objects of my invention are:

First, to provide a covering for a surface of a building, which can be easily and quickly applied;

Second, to provide a covering of flexible 25 roofing material, so constructed that all portions of the roof are covered by at least two thicknesses of the roofing material;

Third, to provide a covering for a building 30 formed of flexible roofing material, which is so constructed and secured to the building as to permit the portions thereof freely to expand and contract, without appreciable buckling or other undesirable distortions of the covering.

35 Fourth, to provide a covering for a building comprising a plurality of rows of shingles arranged in overlapping relation, and means for holding down the outer ends of the shingles to prevent them from being 40 blown up by the wind, or otherwise displaced from their proper positions; and

Finally, to provide a covering of such 45 construction as to give the light and shadow effect of a tile roofing, without the necessity of using an excessive amount of the covering material.

Other objects will appear as this description progresses, reference being had to the accompanying drawings, in which

50 Figure 1 is a plan view of a portion of a roof constructed in accordance with my invention;

Figure 2 is a transverse section therethrough on line 2—2 of Figure 1, and

Figure 3 is a fragmentary plan view on 55 an enlarged scale.

Throughout the several views, similar reference characters will be used for referring to similar parts.

One of the objections to the use of prepared roofing, formed of sheets of fibrous material impregnated with asphalt, or other moisture-repellant material, is that such roofs are flat and monotonous in appearance. Various attempts have been made to overcome this objection by cutting the roofing material up into strips, shingles and other forms, so arranged as to give a light and shadow effect, and thus, to some extent, simulating the appearance of tile roofing, 70 but most of the proposed arrangements have been objectionable for one cause or another.

In some of these previous constructions, considerable difficulty has been experienced through the curling of the strips or shingles. Another objection has been due to the fact that the parts of the roof are not free to expand and contract with changes in temperature. In these constructions, under increased temperature the roofing has a tendency to buckle at various places, thus not only producing an unsightly appearance, but permitting rain to enter. In some of these constructions, at certain points only one thickness of the roofing protects the interior 80 of the building from the weather.

My present invention is designed to overcome all of the above objectionable features of prior construction, and at the same time possesses advantageous features not found 90 in the prior constructions.

Referring to the drawings, wherein I have illustrated one embodiment of my invention, I have shown a portion of a roof comprising the roof boards 5, which act as a supporting surface for a plurality of strips 6 of flexible roofing material, arranged side by side, and in overlapping relation, the edges of the strips being substantially parallel with each other. Each of these strips 100 has formed therein, adjacent its free edge, a plurality of longitudinally spaced pairs of outwardly converging slots 7. A plurality of shingles 8 is transversely arranged on

each strip 6 in longitudinally spaced relation, and each of these shingles is secured to its strip by having its outer corners 8' inserted through a pair of the slots 7, as shown in Figures 1 and 2.

In constructing a building embodying my invention, the lowest strip 6 of roofing material is first applied to the surface to be covered; the shingles 8 are then placed upon 10 the strip and secured thereto by having their outer corners inserted in the slots 7; another strip 6 of material is applied to the first strip in overlapping relation, and nails or other securing devices 9 are driven 15 through the superimposed strip and the shingle and strip beneath the superimposed strip. Preferably, I locate these nails or securing devices, as shown in Figure 1, just inside of the slots 7, so that when the next 20 row of shingles is applied, the shingles will cover the securing devices. These operations are continued until the entire surface is covered.

I prefer to arrange the strips and rows of 25 shingles in such relation to each preceding strip and row of shingles that only one row of fastening devices 9 will pass through each shingle and strip. These fastening devices being arranged longitudinally of the strips 30 and transversely of the shingles, will permit the strips freely to expand and contract in a transverse direction, and the shingles to expand and contract longitudinally without buckling. The slots 7 are of such length 35 that the corners of the shingles fit loosely therein, as shown in Figure 2, so as to permit movement of the shingles through expansion and contraction, and thus prevent any buckling of the outer ends of the 40 shingles, due to changes in temperature. The slots not only perform the function just referred to, but also serve to determine the outline of the exposed portion of the shingles, as is clearly apparent from an inspection of 45 Figure 1, in which the exposed portions of the shingles give an effect of being octagonal in shape. It is, of course, apparent that the slots 7 need not be straight, and that by 50 suitably changing the shape of the slots, different optical effects can be produced. I prefer also to arrange the shingles so that their outer edges 8^a are spaced from the edges 6^a of the corresponding strips 6, thereby leaving a marginal portion of each strip 55 exposed, which tends to exaggerate the thickness of the adjacent end of the shingle, and thus produces the light and shadow effect so much desired in roofs formed of prepared roofing material.

50 From an inspection of the drawing, it will be clear that at all points the surface of the building is covered by at least two thicknesses of the covering material, and that it is practically impossible for rain to gain 65 entrance to the building through the cover-

ing material on account of the great distance which it would have to travel. It will also be apparent that with my construction, exceptionally good drainage is provided for any rain which may work upwardly slight 70 distances beneath the strips or the shingles, and that there is, therefore, very little danger of an accumulation of either water, frost, or ice beneath portions of the roof.

By making the strips of one color, and the 75 shingles of another or other colors, the light and shadow effect can be considerably increased.

While I have described my invention in connection with the roof of a building, it is 80 to be clearly understood that my invention is not limited to this use, but can be used for covering the sides, or any other exposed surface of a building or other structure.

It is also to be understood that my invention is not limited to the details of construction described, but is capable of other adaptations and modifications within the scope 85 of the appended claims.

Having thus described my invention, what 90 I claim is new and desire to secure by Letters Patent of the United States is:

1. The combination with a supporting surface of a plurality of strips of flexible roofing material arranged on said surface in overlapping relation, the free edges of said strips being substantially parallel, said strips being provided at spaced intervals and adjacent their free edges with a plurality of 95 pairs of outwardly converging slots, a plurality of rectangular shingles extending transversely of each of said strips in spaced relation, each of said shingles having its outer corners loosely inserted in one of said pairs of slots, and a nail driven through each 100 of said strips and the next adjacent strip, its superimposed shingle, and said supporting surface, adjacent each of said slots, the 105 head of said nail being concealed by the shingle having its corner secured in said 110 last named slot.

2. The combination with a supporting surface of a plurality of strips of flexible roofing material arranged on said surface in overlapping relation, the free edges of said strips being substantially parallel, said strips being provided at spaced intervals and adjacent their free edges with a plurality of 115 pairs of outwardly converging slots, a plurality of rectangular shingles extending transversely of each of said strips in spaced relation, each of said shingles having its outer corners loosely inserted in one of 120 said pairs of slots, and means for securing said strips and shingles to said surface.

3. The combination with a supporting surface of a plurality of strips of flexible roofing material arranged on said surface in overlapping relation, the free edges of said strips being substantially parallel, said 125

strips being provided at spaced intervals with a plurality of pairs of outwardly converging slots, a plurality of rectangular shingles extending transversely of each of said strips, each of said shingles having its outer corners loosely inserted in one of said pairs of slots, and means for securing said strips and shingles to said surface.

4. The combination with a supporting surface, of a plurality of strips arranged thereon in overlapping relation, the free edges of said strips being substantially parallel, a plurality of shingles extending transversely of each of said strips in spaced relation, the outer end of each of said shingles terminating adjacent the free edge of the strip on which it is superimposed, and means for securing the outer end of each shingle to its strip comprising means which will permit the outer end of said shingle freely to expand or contract in any direction without becoming detached from said strip.

5. The combination with a supporting surface, of a plurality of strips arranged thereon in the overlapping relation, the free edges of said strips being substantially parallel, a plurality of shingles extending transversely of each of said strips, and means for securing the outer end of each shingle to its strip comprising means which will permit the outer end of said shingle freely to expand or contract in any direction without becoming detached from said strip.

35 6. The combination with a supporting surface, of a plurality of strips arranged thereon in overlapping relation, the free edges of said strips being substantially parallel, a plurality of shingles extending transversely of each of said strips, means on said strips for engaging portions of said shingles to secure the latter to the strips, and means for securing said strips to said supporting surface.

7. The combination with a supporting surface, of a plurality of strips of roofing arranged thereon in overlapping relation, a plurality of shingles extending transversely of each of said strips, and means for securing the outer ends of each of said shingles to its strip which determines the visible outline of a portion of the outer end of said shingles.

8. The combination of a strip of roofing material having adjacent one longitudinal edge a plurality of pairs of spaced outwardly converging slots, and a plurality of shingles superimposed on said strip, each of said shingles having the corners at one end thereof loosely inserted in a pair of said slots.

9. The combination of a strip of roofing material having adjacent one longitudinal edge a plurality of pairs of spaced outwardly converging slots, and a plurality of shingles secured to said strip in spaced relation, said shingles terminating inwardly from but adjacent one edge of said strip.

10. The combination of a strip of roofing material having adjacent one longitudinal edge a plurality of pairs of spaced outwardly converging slots, and a plurality of shingles secured to said strip in spaced relation.

11. As an article of manufacture, a strip of flexible roofing having adjacent one edge thereof longitudinally spaced pairs of outwardly converging slots.

12. An article of manufacture comprising a strip of flexible roofing having adjacent one edge thereof longitudinally spaced pairs of slots.

In witness whereof, I hereunto subscribe my name this 27 day of July, 1922.

ROBERT S. MACLEAN.
